DESIGN FOR A LIGHTING FIXTURE

Paul D. Phillips, Elmhurst, Ill., assignor to Benjamin Electric Mfg. Company, Des Plaines, Ill., a corporation of Illinois

Application July 23, 1937, Serial No. 70,590

Term of patent 14 years

To all whom it may concern:

Be it known that I, Paul D. Phillips, a citizen of the United States, residing at Elmhurst, in the county of Du Page and State of Illinois, have invented a new, original, and ornamental Design for a Lighting Fixture, of which the following is a specification, reference being had to the accompanying drawing, forming a part thereof.

The figure is a perspective view of a lighting fixture, showing my new design.

I claim:

The ornamental design for a lighting fixture substantially as shown.

PAUL D. PHILLIPS.
